UNITED STATES PATENT OFFICE.

CLARA KALKBRENNER SCHINDHELM, OF CINCINNATI, OHIO.

MOLD.

1,026,832.

Specification of Letters Patent.

Patented May 21, 1912.

Original application filed May 18, 1908, Serial No. 433,472. Divided and this application filed April 11, 1910. Serial No. 554,739.

To all whom it may concern:

Be it known that I, CLARA KALKBRENNER SCHINDHELM, a citizen of the United States, residing at Cincinnati, in the county of 5 Hamilton and State of Ohio, have invented certain new and useful Improvements in Molds, of which the following is a specification.

My invention relates to the construction 10 of molds used in reproducing the form of a body for use in the manufacture or display of garments or other appliances which must fit accurately to the body, and has for its object the simplification of the operation of 15 obtaining such a mold without undue discomfort to the subject, while at the same time expediting the work of the operator, and making the inner surface of the mold perfectly smooth affording the nearest approach to absolute conformity with the body 20 for which the form is to be made, this application being a division of my application Serial No. 433,472, filed May 18, 1908.

My device consists in a jacket accurately 25 conformed to the figure, said jacket being made in parts secured together in such manner as to be readily separable, and strips of pliable material saturated and coated with an adhesive substance adapted to become dry 30 and brittle and form a rigid structure, such as a mixture of plaster of Paris and water, said strips being placed upon said jacket.

My device consists further in certain other 35 new and novel parts and combinations of parts which will hereinafter be described and pointed out in the appended claims.

In the drawing: Figure 1 is a view showing the jacket as it appears when placed upon a body. Fig. 2 is a detail view showing the manner in which the parts of the jacket are fastened together, and showing a covering of paper or some other suitable material over the joined portions of the jacket. Fig. 3 is a view showing the manner in 45 which the adhesive strips are placed upon the jacket, thus forming the shell or wall of the mold. Fig. 4 is a perspective view of the completed half of the mold.

Referring more particularly to the drawing, I show at 10 a jacket which is to be fitted upon the subject. The parts of said jacket are fastened together by means of a wire 11 passing through slots in the jacket as shown in Fig. 2, thus forming a standing 55 seam or flange 12. The standing seam or

flange 12 supports a partition 13 made of two strips of material each of which is attached to one of the parts of the jacket 10 by means of seams 14 and the two strips of the partition 13 being fastened together 60 near their free edges by means of a seam 15. The ends of the wire 11 may be provided with suitable knobs or knots to prevent their being inadvertently pulled out of the standing seams or flanges 12 during the operation. 65 The standing seams or flanges 12 thus composed extend well up under the chin in front and up the back of the neck in the rear so that the form of the neck may be included in the mold if desired. Additional material is 70 preferably allowed in the jacket 10 to form a shield around the face and hair of the subject, while the sleeves 16 of the jacket may be made of ample length to protect the arms in the same manner.

The jacket with its parts secured together, as above described, is put onto the subject by drawing over the head and arms in the ordinary well known manner. This jacket is composed of an elastic woven material, 80 preferably such as underwear is usually made of, and is made to more accurately conform to the body than it would from its elasticity by drawing the material together whereby folds 17 are formed and through which pins are inserted in the manner illustrated in Fig. 1. The superfluous material may then be cut away along the dotted line 18 shown in Fig. 1, after which the same will appear as shown at 19. The wire passing through the standing seam 12 of the jacket prevents its distortion during the process of conforming the jacket accurately to the figure. After the jacket has been thus accurately conformed to the body and its 90 superfluous material removed, the building of the mold is commenced by applying to the surface of the jacket a series of strips 20 of pliable material saturated and coated with an adhesive substance, the application 100 of the strips preferably being begun at the top of the jacket in the region of the neck and shoulders and being continued downward, each strip being allowed to lap over the preceding one sufficiently to form a joint 105 therewith and produce a continuous and coherent structure covering the jacket 10. This is more clearly shown in Fig. 3 of the drawing. After the first layer of strips of pliable material has been completed cover- 110

ing the jacket and the body to which the jacket has been conformed, the application of a second series of strips 21 is preferable. These strips 21 are placed upon the strips 20 in the same manner that the strips 20 were placed upon the jacket 10. I prefer to employ strips for the second layer of a different color, from that of the strips of the first layer, and in order that the operator may be accurately guided and for the same reason I prefer that the strips 20 of the first layer should be of a different color from that of the material composing the jacket 10. This has the effect of relieving the operator from too close attention in order to avoid the covering of the same surface with strips more than once during the application of the same layer of strips.

It is desirable that the pliable strips 20 of the first layer may be comparatively thin in order that they may be overlapped and at the same time made to conform accurately to the form of the body and the jacket 10 and for this purpose such woven material as 25 muslin, calico or cambric may be used. For the second layer the strips need not be so thin, and preferably are composed of a material adapted to absorb a considerable quantity of the adhesive substance so that 30 the structure of the mold when completed will consist practically of the hardened adhesive substance with the fibers of the materials composing the pliable strips 20 and 21 passing through it. With this object in 35 view such materials as knitted cotton, cotton cloth or cotton flannel may be used to advantage. It is not desirable that the strips 20 and 21 be of any considerable length as more accurate conformity may be 40 attained by using shorter strips, and it is not necessary that the strips be of any greater length than is required to render the handling of them convenient. The adaptability of such comparatively short strips 45 renders it possible to use scraps of material in my improved process. The structure formed by the application of strips being in separate parts, the possibility of passing a strip entirely around the body in the process 50 is precluded, so that a marked distinction from the use of bandages may be noted, rendering it unnecessary to provide a material in a special form for the purpose. Also, the use of the comparatively short 55 strips renders it unnecessary that the strips themselves should be of any considerable elasticity as is required with the use of bandages passing one or more times around the body or limbs. Due to the possibility of 60 using scraps of material and the avoidance of the necessity of providing elastic material as well as the simplicity of the operation of applying the strips, greatly expediting the work, the mold may be very cheaply 65 produced. It will be understood that the

strips thus applied, whether in one or two layers, will, when the application is completed, constitute two distinct structures separated along the middle line of the body in the front and the rear by standing 70 seams 12.

The purpose of providing the standing seams or flanges 12 with the partitions 13 is to prevent the coalescence of the adhesive material with which the strips are saturated and coated and to cover the wire 11 and prevent the contact of the adhesive substance therewith. The adhesive substance best adapted for use in my improved process is a mixture of plaster of Paris and water, the strips being prepared by covering them with the dry plaster and then rolling them ready to be dipped into the water just before they are applied. For the purpose of preventing coalescence of the adhesive 80 substance thus composed the best material of which to construct the partition 13 in the standing seam 12 is paper, preferably of a close texture, adapted to be impervious to the thin mixture constituting the adhesive 85 substance. It is not necessary that the paper be absolutely water proof for this purpose.

After the structure constituted by the flexible strips applied in the manner above set 95 forth has been completed sufficient time is allowed to elapse for the hardening of the adhesive substance, which, with the use of plaster of Paris, consists in the setting of the plaster due to its combination with the 100 water with which it is mixed and which action, as is well known, takes place very quickly. Also, as is well known, when plaster of Paris has been allowed to set perfectly 105 it will be perfectly dry, and it is desirable that the perfect setting of the plaster may be allowed in order that the mold may not be pliable in such degree as to allow of any distortion in handling during its removal from the body. At the same time, the plaster having permeated through the meshes and between the fibers of the material composing the jacket has caused the separable parts of the jacket along with the series of strips which were applied to it, as above 110 described, to constitute an integral structure while the plaster which has thus permeated through the jacket and constitutes, with the jacket, the interior surface of the structure being thoroughly dry will readily separate from the body on which the structure has been formed. In order to remove the structure from the body it is then only necessary to remove one of the knobs or knots placed in the end of the wire 11 and then withdraw said wire 115 from the standing seams or flanges 12. The two parts of the structure are now held together on the body only by the paper or other material forming the partitions 13 and with the use of the ordinary paper for construct- 120 125 130 135

ing these partitions the paper will have become saturated with water and will readily tear along the seam 15 when one part of the structure is drawn away from the other part. In this manner the parts are removed from the body in the shape shown in Fig. 4 of the drawing where one-half of the structure is represented. Thus, it is apparent that when the structure has thus been removed it forms a mold, the inner surface of which constitutes a most accurate reproduction of the form of the body of the subject throughout the extent to which the strips of pliable material have been applied and with the use of plaster or similar material is rigid and well adapted to maintain its shape so that the presence of the subject is not required during the future operations in making the form from the said mold.

The parts of the mold removed from the body, as above set forth, may then be used separately for constructing the form which is the subject matter for another application. The construction of the form consists, briefly, in applying to the interior surface of the form a series of pieces of fibrous material preferably dry on their sides next to the inner surface, but with their sides coated with an adhesive material which is adapted to retain its adhesiveness and assume a tenacious condition when dry, such as glue or paste. These pieces of fibrous material are applied so that they slightly overlap each other to form a continuous and coherent structure in a manner similar to the overlapping of the pliable strips 20 and 21 in the construction of the mold. When these pieces of fibrous material have been placed upon the inner surface of the mold close to the standing seams 12, the two parts of the mold may be placed together and tied in a suitable manner to hold them together. Then the adhesive strips may be placed across the joints and thereby produce a complete form. The fibrous pieces of material may be applied in any desired number of layers to cause the form to have walls of any desired thickness. When the adhesive strips comprising the form have been allowed to dry thoroughly the parts of the mold may be removed from the form.

Although the foregoing description has been devoted to the description of producing the mold for producing the form of the bust and hips of the subject, it may be readily seen that my improved process is equally well adapted for reproducing the entire figure, including the body and limbs of

the subject when it may be desired to do so for the production of forms for fitting and exhibiting such articles as bathing suits and all athletic garments. For reproducing the entire figure of the subject instead of allowing the standing seam 12 to follow the middle line of the body in front and rear, it may be caused to follow lines along the sides of the body and the limbs in such position as is best adapted for allowing the separation of the parts of the mold and removing it from the body and limbs. It will be understood that it is possible to produce the form of the body in many desirable positions.

It will be understood that while particular material has been recommended for use throughout the description of my invention, the substitution of materials well known to have properties like those mentioned may be used.

In view of the variety of uses for which my invention is adapted, I do not wish to be confined to the exact details in the illustrations herein set forth.

What I claim as new and desire to secure by Letters Patent is:

1. The process of forming a mold to be used in the manufacture of garment forms which consists first in applying to the body of a person a jacket formed of a plurality of parts detachably connected together, then applying to each part of said jacket separately, pliable material which is adapted to adhere to said parts respectively, then allowing the same to dry and harden, and then removing each part of the mold from the person.

2. The herein described process which consists in first forming a flexible jacket in separate parts, each separate part having outwardly projecting flanges along its edges, then detachably connecting said flanges together, then covering said outwardly projecting flanges and detachably securing said parts together, then placing said jacket upon a person and conforming it to the figure, then placing pliable and adhesive material on said parts respectively and between the outwardly projecting flanges and allowing the same to dry and harden to form a rigid structure, then removing the detachable connections and removing the mold in parts.
